(57) **CLAIM**

The ornamental design for a coffee homogenization tool as shown and described.

DESCRIPTION

1. Coffee homogenization tool

1.1 : shows a left perspective view of the coffee homogenization tool;

1.2 : shows a front view thereof;

1.3 : shows a right perspective view thereof;

1.4 : shows a top view thereof;

1.5 : shows a right view thereof;

1.6 : shows a rear view thereof;

1.7 : shows a left view thereof; and

1.8 : shows a bottom view thereof.

The claimed design represents a coffee homogenization tool for homogenizing ground coffee. The broken lines in the drawings, depict portions of the coffee homogenization tool and form no part of the claimed design.
